[57] CLAIM

The ornamental design for a wrist transmitter, as shown.

DESCRIPTION

FIG. 1 is a front plan view of a wrist transmitter embodying my novel design;

FIG. 2 is a bottom plan view of the novel design depicted in FIG. 1;

FIG. 3 is a left side elevational view of the wrist transmitter depicted in FIG. 1;

FIG. 4 is a right side elevational view of the wrist transmitter depicted in FIG. 1;

FIG. 5 is a front elevational view of the wrist transmitter depicted in FIG. 1;

FIG. 6 is a rear elevational view of the wrist transmitter depicted in FIG. 1;

FIG. 7 is a top plan view of the wrist transmitter depicted in FIG. 1 with the aerial extended;

FIG. 8 is a top plan view of a further embodiment of a wrist transmitter embodying my novel design;

FIG. 9 is a bottom plan view of the wrist transmitter depicted in FIG. 8;

FIG. 10 is a left side elevational view of the wrist transmitter depicted in FIG. 1;

FIG. 11 is a right side elevational view of the wrist transmitter depicted in FIG. 8;

FIG. 12 is a front elevational view of the wrist transmitter depicted in FIG. 8;

FIG. 13 is a rear elevational view of the wrist transmitter depicted in FIG. 8; and

FIG. 14 is a front plan view of the wrist transmitter depicted in FIG. 1 with the aerial extended.
